FREDERICK ELWOOD STRUVE, OF PHILADELPHIA, PENNSYLVANIA

Application filed January 2, 1932. Serial No. 42,356. Term of patent 3½ years.

To all whom it may concern:

Be it known that I, FREDERICK ELWOOD STRUVE, a citizen of the United States, residing at Philadelphia, county of Philadelphia, and State of Pennsylvania, have invented a new, original, and ornamental Design for a Stocking, of which the following is a specification, reference being had to the accompanying drawing, forming part thereof.

Figure 1 is a side elevation of the stocking.

Figure 2 as shown in the application drawing is a slightly enlarged view of a portion

of the stocking leg fabric, but which in the reduction to patent size will show the fabric approximately actual size.

The leg blank of the stocking extending from the cuff or welt to the sole is of a design as illustrated at each end portion of the leg blank in Figure 1.

I claim:

The ornamental design for a stocking as shown and described.

FREDERICK ELWOOD STRUVE.
